CLAIM

The ornamental design for a portable device holder, as shown and described.

DESCRIPTION

FIG. 1 is a rear perspective view of a portable device holder; FIG. 2 is a front perspective view of the portable device holder; FIG. 3 is a front elevational view of the portable device holder; FIG. 4 is a rear elevational view of the portable device holder; FIG. 5 is a bottom plan view of the portable device holder; FIG. 6 is a top plan view of the portable device holder; FIG. 7 is a right elevational view of the portable device holder; FIG. 8 is a left elevational view of the portable device holder; FIG. 9 is a rear perspective view of a base portion of a portable device holder shown separately for clarity of illustration; FIG. 10 is a front perspective view of the base portion of the portable device holder shown separately for clarity of illustration; FIG. 11 is a front elevational view of the base portion of the portable device holder shown separately for clarity of illustration;

FIG. 12 is a rear elevation view of the base portion of the portable device holder shown separately for clarity of illustration;

FIG. 13 is a bottom plan view of the base portion of the portable device holder shown separately for clarity of illustration;

FIG. 14 is a top plan view of the base portion of the portable device holder shown separately for clarity of illustration;

FIG. 15 is a right elevation view of the base portion of the portable device holder shown separately for clarity of illustration;

FIG. 16 is a left elevation view of the base portion of the portable device holder shown separately for clarity of illustration;

FIG. 17 is a rear perspective view of a portable device attachment portion of a portable device holder shown separately for clarity of illustration;

FIG. 18 is a front perspective view of the portable device attachment portion of the portable device holder shown separately for clarity of illustration;

FIG. 19 is a front elevation view of the portable device attachment portion of the portable device holder shown separately for clarity of illustration;

FIG. 20 is a rear elevation view of the portable device attachment portion of the portable device holder shown separately for clarity of illustration;

FIG. 21 is a top plan view of the portable device attachment portion of the portable device holder shown separately for clarity of illustration;

FIG. 22 is a bottom plan view of the portable device attachment portion of the portable device holder shown separately for clarity of illustration;

FIG. 23 is a right elevation view of the portable device attachment portion of the portable device holder shown separately for clarity of illustration; and,

FIG. 24 is a left elevation view of the portable device attachment portion of the portable device holder shown separately for clarity of illustration.
